RAILWAY SIGNALING

Ralph R. Kemmerer, Swissvale, Pa., assignor to
 The Union Switch & Signal Company, Swiss-
 vale, Pa., a corporation of Pennsylvania

Application September 29, 1938, Serial No. 232,384

13 Claims. (Cl. 246—50)

My invention relates to railway signaling, and particularly to apparatus for controlling wayside signals by coded and steady currents carried by a pair of line conductors between succeeding signal locations.

I shall describe three forms of apparatus embodying my invention, and shall then point out the novel features thereof in claims.

In the accompanying drawings, Figs. 1a and 1b, when placed end to end with Fig. 1a on the left, constitute a diagrammatic view showing one form of apparatus embodying my invention for the control of five block automatic color light signals; Fig. 2 is a diagrammatic view, showing a modification of the apparatus shown adjacent each signal location in Figs. 1a and 1b, for the control of three block automatic color light signals; and Fig. 3 is a diagrammatic view showing a modification of the apparatus of Fig. 2 for controlling combined semaphore and color light signals.

Similar reference characters refer to similar parts in each of the several views.

Referring first to Figs. 1a and 1b, the reference characters 7 and 7a designate the rails of a stretch of railway track over which traffic normally moves in the direction indicated by the arrow, which I shall assume to be the eastbound direction. Rails 7 and 7a are divided by insulated joints 8 into blocks 11—12, 12—13, 13—14, 14—15, and 15—16.

Each of these blocks as shown is further divided by other insulated joints 8 into two sections, block 11—12, for example, being divided into sections 11—11a and 11a—12. It is not necessary, for the purpose of my invention, that the blocks be divided as shown. In some instances it might be satisfactory to have only one section for each block, and in other instances it might be necessary to divide each block into more than two sections. Each track section is provided with a track circuit comprising a battery 9 connected across the rails adjacent one end of the section, and a relay, designated by the reference character TR with a distinguishing prefix, connected across the rails adjacent the opposite end of the section.

Adjacent the entrance end of each of the blocks which are shown complete, and also adjacent the entrance end of the block to the right of point 11 shown in part in Fig. 1b, a signal is located for governing eastbound traffic movements. These signals are designated by the reference numerals 1, 2, 3, 4, 5 and 6, respectively.

It is here assumed that each of the signals

is of the color light type comprising an upper group of lamps designated by the reference character A, a middle group of lamps designated by the reference character B, and a lower group of lamps designated by the reference character C. 5 Each upper group of lamps comprises a green lamp G, a yellow lamp Y, and a red lamp R; and each middle group and each lower group of lamps comprises a green lamp G and a red lamp R. It is to be understood, however, that my invention is not limited to signals of this particular type.

The lighting of the lamps of each of the signals 1—6, inclusive, is controlled by a polarized signal control relay having a slow release neutral armature, designated by the reference character HD with a numerical prefix corresponding to the reference numeral for its signal, and by two slow release repeater relays designated by the reference characters ADP and BDP, respectively, with a 10 prefix corresponding to the reference character for the associated signal. The slow release repeater relays ADP and BDP are controlled by front contacts of normal and reverse slow release decoding relays designated by the reference characters AD and BD, respectively, with numerical prefixes corresponding to the reference character 15 for the associated signal.

Each normal decoding relay AD is controlled by a normal decoding transformer designated by 30 the reference character AT with a prefix corresponding to the reference character for the associated signal, and by normal contacts of a polarized code following relay designated by the reference character CP with a prefix corresponding 35 to the reference character for the associated signal. Each reverse decoding relay BD is controlled by a reverse decoding transformer designated by the reference character BT with a prefix corresponding to the reference character for 40 the associated signal, and by reverse contacts of the polarized code following relay CP for the associated signal.

Each normal decoding transformer AT is controlled by normal contacts of the code following 45 relay CP for the associated signal, and each reverse decoding transformer BT is controlled by reverse contacts of the associated code following relay CP.

Each code following relay CP is responsive to 50 current of a given polarity, which I shall call normal polarity, for closing its contacts 17 and 20, which I have called normal contacts, in the inclined left-hand position as shown in the drawings, which I shall call the normal position. Each 55

code following relay CP is also responsive to current of the opposite or reverse polarity for closing its contacts 21 and 24, which I have called reverse contacts, in the inclined right-hand position as shown in the drawings, which I shall call the reverse position.

The contacts 17 and 20 become closed in the vertical position, which I shall call the deenergized position, when the corresponding relay CP becomes deenergized, and remain closed in that position when the corresponding CP relay becomes energized by current of reverse polarity. The contacts 21 and 24 similarly become closed in the vertical position when the corresponding relay CP becomes deenergized, and remain closed in that position when their CP relay becomes energized by current of normal polarity.

Each relay CP is energized by current carried over a pair of conductors 35 and 42 between the associated signal and the next signal in advance, and controlled by the track relays TR for the block of the associated signal and by the slow release repeater relays and polarized signal control relay for the next signal in advance and also by a coding device designated by the reference character CT with a prefix corresponding to the reference character for the next signal in advance.

Each polarized signal control relay HD is controlled over the same contacts as the code following relay CP for the same signal, and is also controlled by back contacts of the decoding relays AD and BD for the same signal.

Each coding device CT is constantly connected to the terminals b and o of a source of current not shown in the drawings, which can be of any suitable form, but which is here assumed to be a source of constant direct current. The coding devices CT operate to open and close their contacts at any suitable frequency such, for example, as 180 cycles per minute.

As shown in Fig. 1b, the track section immediately in advance of signal 1 is occupied by a train W. The indication displayed by each of the signals 1 to 6, inclusive, under this condition, and the meanings of these indications are stated in the following table:

Sig- nal	Indication displayed			Meaning of indication
	Group A	Group B	Group C	
1	Red	Red	Red	First block ahead is occupied.
2	Yellow	Red	Red	First block ahead is clear, second block is occupied.
3	Yellow	Red	Green	First two blocks ahead clear, third block occupied.
4	Red	Green	Red	First three blocks clear, fourth block occupied.
5	Yellow	Green	Red	First four blocks clear, fifth block occupied.
6	Green	Red	Red	First five blocks ahead are clear.

I shall now describe the manner in which these indications are displayed when a train W is in the section immediately ahead of signal 1. Under this condition, relay 1TR is deenergized, and hence the circuits for controlling relay 1CP, only a portion of which is shown, are open at contacts 36 and 41 of relay 1TR. The circuits for relay 1HD are also open at these same contacts. Relay 1CP being deenergized, relays 1AD and 1BD controlled by transformers 1AT and 1BT, respectively, and by relay 1CP will be deenergized, and relays 1AD and 1BD controlled by relays 1AD and 1BD, respectively, will also be deenergized.

Lamp R of the upper group A of signal 1 is

therefore lighted by a circuit passing from terminal b, through the back points of contacts 25, 26 and 27 of relays 1AD, 1BD and 1HD, respectively, and lamp R of group A to terminal o. Lamp R of the middle group B of lamps of signal 5 is also lighted by a circuit passing from terminal b, through the back points of contacts 28 and 29 of relays 1AD and 1BD, respectively, and lamp R to terminal o. Lamp R of the lower group of lamps C of signal 1 is lighted by a circuit passing from terminal b, through the back point of contact 30 of relay 1HD, and lamp R to terminal o.

At this time, relay 2HD is energized by a circuit passing from terminal b, through the back points of contacts 31, 32, and 33 of relays 1HD, 1BD and 1AD, respectively, contact 34 of relay a2TR, conductor 35, contact 36 of relay 2TR, conductor 37, contacts 38 and 39 of relays 2BD and 2AD, respectively, winding of relay 2HD, conductor 40, contact 41 of relay 2TR, conductor 42, contact 43 of relay a2TR, and the back points of contacts 44, 45 and 46 of relays 1AD, 1BD and 1HD, respectively, to terminal o. It will be noted that code following relay 2CP is also energized by the circuit just traced between terminals b and o and contacts 36 and 41, respectively of relay 2TR, and then including the windings of relay 2CP. Since the current flowing in this circuit is constant direct current of what I shall term reverse polarity, contact 17 of relay 2CP is constantly closed in the deenergized position, and contact 21 of relay 2CP is constantly closed in the reverse position. With these contacts 17 and 21 constantly closed, there will be no current generated in the secondary windings of decoding transformers 2AT and 2BT, and hence relays 2AD and 2BD will remain deenergized. Relays 2ADP and 2BDP are therefore also deenergized.

With relay 2HD energized and relays 2ADP and 2BDP deenergized, the yellow lamp Y of the upper group of lamps A of signal 2 will be lighted by a circuit passing from terminal b, through the back points of contacts 25 and 26 of relays 2ADP and 2BDP, respectively, the front point of contact 27 of relay 2HD, and lamp Y of group A to terminal o. Lamp R of the middle group B of lamps of signal 2 is lighted by a circuit which is exactly like the circuit previously traced for lamp R of the middle group of lamps B of signal 1. Lamp R of group C of signal 2 is, however, lighted by a circuit which is different from the circuit previously traced for lamp R of group C of signal 1. The circuit for lamp R of group C of signal 2 passes from terminal b, through the front point of contact 30 of relay 2HD, contact 41 of relay 2HD in the reverse or right-hand position, and lamp R of group C of signal 2 to terminal o.

Relay 3HD is energized by steady current of normal polarity in a circuit passing from terminal b, through contact 48 of relay 2HD closed in the reverse position, front point of contact 46 of relay 2HD, back points of contacts 45 and 44 of relays 2BDP and 2ADP, respectively, contact 43 of relay a3TR, conductor 42, contact 41 of relay 3TR, conductor 40, winding of relay 3HD, contacts 39 and 38 of relays 3AD and 3BD, respectively, conductor 37, contact 36 of relay 3TR, conductor 35, contact 34 of relay a3TR, back points of contacts 33 and 32 of relays 2ADP and 2BDP, respectively, the front point of contact 31 of relay 2HD, and contact 49 of relay 2HD closed in the right-hand position, to terminal o. Relay 3CP is also energized by steady current of normal polarity by the circuit traced for relay 3HD between terminals b and o and contacts 41 and 36, 75

respectively, of relay 3TR, and then including the windings of relay 3CP. Contacts 17 and 20 of relay 3CP are therefore closed in the left-hand or normal position, and contacts 21 and 24 of relay CP are closed in the deenergized position. Since these contacts are constantly closed, no current is generated in the secondary windings of decoding transformers 3AT and 3BT, and hence relays 3AD and 3BD and, in turn, relays 10 3ADP and 3BDP remain deenergized.

Under these conditions, lamp Y of the top group A of signal 3 is lighted by a circuit which is exactly similar to the circuit previously traced for lamp Y of the top group of lamps A of signal 2. Lamp R of the middle group B of signal 15 3 is also lighted by a circuit which is exactly similar to the circuit previously traced for lamp R of group B of signal 1. Lamp G of the lowest group C of signal 3 is now lighted by a circuit 20 passing from terminal b, through the front point of contact 30 of relay 3HD, contact 41 of relay 3HD closed in the left-hand or normal position, and lamp G of group C of signal 3 to terminal o.

With relay 3HD energized by current of normal polarity, and with relays 3ADP and 3BDP deenergized, code following relay 4CP is energized by coded current of reverse polarity passing from terminal b, through contact 50 of coding device 3CT, which is opening and closing at a frequency such for example as 180 cycles per minute, contact 49 of relay 3HD closed in the left-hand position, front point of contact 31 of relay 3HD, back points of contacts 32 and 33 of relays 3BDP and 3ADP, respectively, contact 34 of relay a4TR, conductor 35, contact 36 of relay 4TR, windings of relay 4CP, contact 41 of relay 4TR, conductor 42, contact 43 of relay a4TR, back points of contacts 44 and 45 of relays 3ADP and 3BDP, respectively, front point of contact 46 of relay 3HD, contact 48 of relay 3HD closed in the left-hand position, and contact 51 of coding device 3CT to terminal o. With code following relay 4CP energized by coded current of reverse polarity, contact 17 of this relay will remain constantly closed in the deenergized position, and hence no current will be generated in the secondary winding of transformer 4AT. Relays 4AD and 4ADP will therefore remain deenergized.

Contacts 21 and 24 of relay 4CP, however, close alternately at the reverse and deenergized positions, causing current to be generated in the secondary winding 23 of decoding transformer 4BT. This is due to current flowing from terminal b, through contact 21 in its reverse position, and the upper half of primary winding 22 of transformer 4BT to terminal o, alternately with current flowing from terminal b, through contact 21 closed in the deenergized position, and through the lower portion of primary winding 22 of decoding transformer 4T to terminal o.

Slow release decoding relay 4BD is therefore energized by current flowing from the upper portion of the secondary winding 23 of transformer 4BT, through contact 24 of relay 4CP closed in the right-hand position, and the winding of relay 4BD to a mid-point of secondary winding 23, alternately with current flowing from the lower portion of secondary winding 23 of transformer 4BT, through contact 24 of relay 4CP closed in the deenergized position, and the winding of relay 4BD to the mid-point of secondary winding 23. With relay 4BD energized, relay 4HD is deenergized on account of its control circuits being open at a back contact of relay 4BD. Relay 4BD

being energized, its contact 52 will be closed, causing relay 4BDP to be energized by its circuit passing from terminal b, through contact 52 of relay 4BD, and the winding of relay 4BDP to terminal o.

With relay 4BDP energized and relay 4ADP deenergized, lamp R of the top group A of signal 4 will be lighted by current passing from terminal b, through the back point of contact 25 of relay 4ADP, front point of contact 26 of relay 4BDP, and lamp R of group A to terminal o. Lamp G of the middle group B of the lamps of signal 4 is lighted by current passing from terminal b, through the back point of contact 28 of relay 4ADP, front point of contact 29 of relay 4BDP, and lamp G of group B of signal 4 to terminal o. Lamp R of the bottom group C of the lamps of signal 4 is now lighted by a circuit passing from terminal b, through the back point of contact 30 of relay 4HD, and lamp R of group C to terminal o.

With relay 4BDP energized, and relay 4ADP deenergized, relay 5CP will be energized by coded current of normal polarity passing from terminal b, through contact 50 of coding device 4CT, front point of contact 45 of relay 4BDP, back point of contact 44 of relay 4ADP, contact 43 of relay a5TR, conductor 42, contact 41 of relay 5TR, windings of relay 5CP, contact 36 of relay 5TR, conductor 35, contact 34 of relay a5TR, back point of contact 33 of relay 4ADP, front point of contact 32 of relay 4BDP, and contact 51 of coding device 4CT to terminal o. With relay 5CP energized by coded current or normal polarity, contacts 17 and 20 of relay 5CP close alternately in their left-hand and deenergized positions, causing current to be generated in secondary winding 19 of decoding transformer 5AT, which energizes relay 5AD. Contacts 21 and 24 of relay 5CP are constantly closed in the deenergized position, and therefore no current is generated in the secondary winding of the transformer 5BT, and hence relay 5BD remains deenergized. With relay 5AD energized, relay 5HD is deenergized on account of its circuits being open at a back contact of relay 5AD. With relay 5AD energized, slow release repeating relay 5ADP will be energized by a circuit passing from terminal b, through contact 53 of relay 5AD, and the winding of relay 5ADP to terminal o.

With relay 5ADP energized and relay 5BDP deenergized, lamp Y of the top group A of the lamps of signal 5 will be energized by a circuit passing from terminal b, through the front point of contact 25 of relay 5ADP, back point of contact 54 of relay 5BDP, and lamp Y of group A to terminal o. Lamp G of middle group B of the lamps of signal 5 is now lighted by a circuit passing from terminal b, through the front point of contact 28 of relay 5ADP, back point of contact 55 of relay 5BDP, and lamp G of group B to terminal o. Lamp R of the bottom group C of the lamps of signal 5 is now lighted by a circuit similar to the circuit previously traced for lamp R of bottom group C of signal 1.

With relay 5ADP energized, code following relay 6CP is energized by coded current impulses of normal polarity alternately with coded current impulses of reverse polarity, the coded current of normal polarity passing from terminal b, through the front point of contact 56 of coding device 5CT, front point of contact 44 of relay 5ADP, contact 43 of relay a6TR, conductor 42, contact 41 of relay 6TR, windings of relay 6CP, contact 36 of relay 6TR, conductor 35, contact 34 of relay 75

a6TR, front point of contact 33 of relay 5ADP, and the front point of contact 51 of coding device 5CT to terminal o. The circuit by which relay 6CP receives coded current of reverse polarity is the same as the circuit just traced, except that current is supplied to the circuit from terminal b, through the back point of contact 57 of coding device 5CT, and returns to terminal o through the back point of contact 56 of coding device 5CT.

With relay 6CP thus energized by coded current impulses of normal polarity alternately with impulses of reverse polarity by the circuit just traced through the front and back points of contacts 56 and 57 of coding device 5CT, contacts 17 and 20 will be operated to the left-hand position by the impulses of normal polarity, and will be operated to the deenergized position when each impulse of normal polarity ceases. Contacts 21 and 24 of relay 6CP will be operated to the right-hand position by the impulses of reverse polarity supplied to the windings of relay 6CP, and will return to the deenergized position when each impulse of reverse polarity ceases.

Current will therefore be generated in the secondary windings of both decoding transformers 6AT and 6BT, causing both decoding relays 6AD and 6BD to be energized. The circuit for relay 6HD is now open at back contacts of both relays 6AD and 6BD, and relay 6HD therefore remains deenergized. With relays 6AD and 6BD energized, relays 6ADP and 6BDP, respectively, will also be energized.

With both relays 6ADP and 6BDP energized, lamp G of the top group A of the lamps of signal 6 will be lighted by a circuit passing from terminal b, through the front points of contacts 25 and 54 of relays 6ADP and 6BDP, respectively, and lamp G to terminal o. Lamp R of middle group B of the lamps of signal 6 is now lighted by a circuit passing from terminal b, through the front points of contacts 28 and 55 of relays 6ADP and 6BDP, respectively, and lamp R of group B to terminal o. Lamp R of the bottom group C of the lamps of signal 6 is lighted by a circuit similar to the circuit previously traced for lamp R of group C of signal 1.

The code following relay for the next signal in the rear of signal 6 will now be energized, through circuits including front and back points of contacts 56 and 57 of coding device 6CT, by coded impulses of normal polarity alternately with coded impulses of reverse polarity.

Referring now to Fig. 2, a diagrammatic view is here shown of a modified form of each signal shown in Figs. 1a and 1b, and of the apparatus for controlling each of these signals for a three block automatic signaling system. As here shown, each signal has only two groups of lamps, the upper group designated by the reference character A, and the lower group designated by the reference character B. Each upper group comprises a green lamp G, a yellow lamp Y, and a red lamp R as in Figs. 1a and 1b, and each lower group B comprises a green lamp G and a red lamp R.

In view of the showing in Figs. 1a and 1b, and of the foregoing description of the apparatus shown in Figs. 1a and 1b, it is believed that the operation of the three block signaling system can be readily followed with only the one signal location shown in Fig. 2.

As shown in Fig. 2, each signal is controlled by a polarized signal control relay HD, as in Figs. 1a and 1b, and by only one slow release repeating relay, designated by the reference character ADP. The other slow release repeating relay, together

with its decoding relay and decoding transformer shown in Figs. 1a and 1b, are omitted from Fig. 2. The code following relay CP here has only one pair of contacts 17 and 20 which are operated similarly to the contacts having the same reference characters in Figs. 1a and 1b. A slow release approach lighting relay designated by the reference character ER is here shown. The other portions of the apparatus, including coding device CT, decoding transformer AT, decoding relay AD, and slow release repeating relay ADP operate as in Figs. 1a and 1b.

The indications displayed by each signal in the three block signaling system, such, for example, as signal 4a shown in Fig. 2, under various traffic conditions, and the meanings of these indications, are stated in the following table:

Indication displayed		Meaning of indication	20
Group A	Group B		
Red.....	Red.....	First block ahead occupied.	
Yellow....	Red.....	First block clear, second block occupied.	
Yellow...	Green...	First two blocks ahead clear, third block occupied.	25
Green....	Red....	First three blocks clear.	

With three blocks clear in advance of signal 4a shown in Fig. 2, relay CP for signal 4a will be energized by coded current of normal polarity in a circuit a portion of which is shown adjacent the signal 4a, and the rest of which is exactly similar to the portions shown adjacent 4a for the relay CP for the next signal in the rear. The circuit by which relay CP for signal 4a is energized, with three blocks clear in advance of signal 4a, therefore passes from terminal b, through the winding of an approach lighting relay ER for the next signal in advance of signal 4a, contact 58 operated by a coding device CT for the next signal in advance of signal 4a, front point of contact 59 and back point of contact 60 of relays ADP and HD, respectively, for the next signal in advance of signal 4a, contact 43 of relay a4TR for the block of signal 4a, conductor 42, contact 41 of relay 4TR, winding of relay CP, contact 36 of relay 4TR, conductor 35, contact 34 of relay a4TR, and back point of contact 61 and front point of contact 62 of relays HD and ADP for the next signal in advance of signal 4a, to terminal o.

With relay CP thus energized by coded current of normal polarity, its contacts 17 and 20 will be closed alternately in its left-hand and deenergized positions at a frequency corresponding to the frequency at which the coding device CT for the next signal in advance of signal 4a opens its contact 58. Current will therefore be generated in secondary winding 19 of decoding transformer AT, which will energize decoding relay AD. With decoding relay AD energized, slow release repeater relay ADP will be energized by a circuit passing from terminal b, through the front point of contact 53 of relay AD, and the winding of relay ADP to terminal o.

With relay ADP energized, lamp G of the upper group A of signal 4a will become lighted, when a train enters the block in the rear of signal 4a, by a circuit passing from terminal b, through contact 63 of relay ER, front point of contact 64 of relay ADP, and lamp G of group A of signal 4a to terminal o. At the same time, lamp R of group B of the lamps of signal 4a will become lighted by a circuit passing from terminal b, through contact 63 of relay ER, front

point of contact 65 of relay ADP, and lamp R of group B to terminal o.

When a train passes signal 4a, relay 4TR will become deenergized, thereby opening, at its contacts 36 and 41, the circuits for relays CP and HD. Relays AD and ADP will therefore also be deenergized, and lamp R of the upper group A of the lamps of signal 4a will then become lighted by a circuit passing from terminal b, through contact 63 of relay ER, back points of contacts 64 and 66 of relays ADP and HD, respectively, and lamp R of signal 4a to terminal o. At the same time, lamp R of the lower group of lamps B of signal 4a will become lighted by a circuit passing from terminal b, through contact 63 of relay ER, back points of contacts 65 and 67 of relays ADP and HD, respectively, and lamp R of group B to terminal o.

When the train clears the block of signal 4a and occupies the second block in advance of signal 4a, relay HD for signal 4a will become energized by steady current of reverse polarity passing from terminal b, through the winding of relay ER for the next signal in advance of signal 4a, back points of contacts 62 and 61 of relays ADP and HD, respectively, for the next signal in advance of signal 4a, contact 34 of relay a4TR, conductor 35, contact 36 of relay 4TR, winding of relay HD, contact 39 of relay AD, contact 41 of relay 4TR, conductor 42, contact 43 of relay a4TR, and the back points of contacts 69 and 58 of relays HD and ADP, respectively, for the next signal in advance of signal 4a, to terminal o. Relay CP for signal 4a will now be energized by the circuit traced for relay HD between terminals b and o and contacts 36 and 41, respectively, of relay 4TR, and then including the winding of relay CP. With relay CP thus energized by steady current of reverse polarity, contacts 17 and 20 of relay CP will remain closed in the deenergized position, and hence no current will be generated in the secondary winding of decoding transformer AT for signal 4a. Relays AD and ADP for signal 4a will therefore be deenergized.

With relay ADP deenergized and relay HD energized by current of reverse polarity, lamp Y of upper group A of the lamps of signal 4a, when a train enters the block to the rear of signal 4a, will become lighted by a circuit passing from terminal b, through contact 63 of relay ER, back point of contact 64 of relay ADP, front point of contact 66 of relay HD, and lamp Y of group A of signal 4a to terminal o. At the same time, lamp R of the lower group B of the lamps of signal 4a will become lighted by a circuit passing from terminal b, through contact 63 of relay ER, back point of contact 65 of relay ADP, front point of contact 67 of relay HD, contact 69 of relay HD closed in the right-hand or reverse position, and lamp R of group B of signal 4a to terminal o.

When the first train clears the first two blocks in advance of signal 4a and occupies the third block in advance of this signal, relay HD for signal 4a will become energized by steady current of normal polarity flowing in a circuit passing from terminal b, through relay ER for the next signal in advance of signal 4a, contact 68 in the reverse position and front point of contact 60, both of relay HD for the next signal in advance of signal 4a, contact 43 of relay a4TR, conductor 42, contact 41 of relay 4TR, contact 39 of relay AD, winding of relay HD, contact 36 of relay 4TR, conductor 35, contact 34 of relay a4TR,

and front point of contact 61 of relay HD for the next signal in advance of signal 4a to terminal o. Relay CP for signal 4a will now also be energized by steady current of normal polarity, causing contacts 17 and 20 of relay CP to remain closed constantly in their left-hand position. With contacts 17 and 20 of relay CP constantly closed, no current will be generated in secondary winding 19 of decoding transformer AT, and hence relays AD and ADP will remain deener- 10 gized.

With relay ADP deenergized and relay HD now energized by current of normal polarity, lamp Y of upper group A of signal 4a, while a train occupies the first block in the rear of signal 4a, will remain lighted by the circuit previously traced for this lamp. Lamp G of lower group B of the lamps of signal 4a will now be lighted by a circuit passing from terminal b, through contact 63 of relay ER, back point of contact 65 of relay ADP, front point of contact 67 of relay HD, contact 69 of relay HD closed in the left-hand position, and lamp G of group B of signal 4a to terminal o.

When the first train clears the third block in advance of signal 4a, so that the first three blocks in advance of signal 4a are unoccupied, code following relay CP for signal 4a will again become energized by coded current of normal polarity, this time passing from terminal b, through the winding of relay ER for the next signal in advance of signal 4a, contact 58 of coding device CT for the next signal in advance of signal 4a, contact 68 in the normal position and contact 60 closed at the front point, both of relay HD for the next signal in advance of signal 4a, contact 43 of relay a4TR, conductor 42, contact 41 of relay 4TR, winding of relay CP, contact 36 of relay 4TR, conductor 35, contact 34 of relay a4TR, and the front point of contact 61 of relay HD for the next signal in advance of signal 4a, to terminal o. When a second train now occupies the first block in the rear of signal 4a, lamp G of group A of signal 4a and lamp R of group B of signal 4a will again become lighted as previously described.

Referring now to Fig. 3, a diagrammatic view is here shown of a modified form of the apparatus shown in Fig. 2 for controlling combined semaphore and color light signals in a three block automatic signaling system. As shown in Fig. 3, each signal has an upper unit A including an upper quadrant semaphore arm 82 and a lamp 81 which, upon becoming lighted, shines through the green, yellow or red lens which is moved in front of lamp 81 when arm 82 moves to its 90, 45 or 0° position, respectively. Each signal has also a lower unit B which comprises a yellow lamp Y.

Whereas when light signals are used, as shown in Figs. 1a, 1b and 2, a slow release repeater such as relay ADP is desirable in order to prevent erroneous flashing of a red indication under given conditions, the operation of semaphore signals is such that the slow release repeater relays are not needed for the control of semaphore signals, and therefore no ADP relay is shown in Fig. 3. The line circuit for controlling each relay HD is pole changed, in Fig. 3, by contacts 71 and 73 operated by the next signal in advance instead of by contacts of a relay ADP as in Fig. 2. Otherwise, the various parts of the apparatus shown in Fig. 3 for controlling each signal are controlled similarly to the corresponding parts shown in Fig. 2.

The indications displayed by each signal in a three block signal system of the type, such, for example, as signal 4b shown in Fig. 3, under various traffic conditions, and the meanings of 5 these indications are stated in the following table:

Indication displayed		Meaning of indication
Unit A	Unit B	
Arm in 0° or horizontal position.		First block ahead is occupied.
Arm in 45° position.		First block ahead is clear, second block is occupied.
15 Arm in 45° position.	Lamp Y of unit C lighted.	First two blocks ahead clear, third block occupied.
Arm in 90° position.		First three blocks ahead are clear.

20 With three blocks clear in advance of signal 4b, shown in Fig. 3, relay CP for signal 4b will be energized by coded current of normal polarity in a circuit a portion of which is shown adjacent 25 signal 4b, and the rest of which is exactly similar to the portion shown adjacent 4b for the relay CP for the next signal in the rear. The circuit by which relay CP for signal 4b is energized, with three blocks clear in advance of signal 4b, 30 therefore passes from terminal b, through the winding of an approach lighting relay ER for the next signal in advance of signal 4b, contact 58 of coding device CT for the next signal in advance, front point of contact 70 of relay AD and back 35 point of contact 60 of relay HD, both for the next signal in advance of signal 4b, contact 71 operated by the next signal in advance of signal 4b, contact 43 of relay a4TR, conductor 42, contact 41 of relay 4TR, winding of relay CP, conductor 40 12, and contact 13 operated by the next signal in advance of signal 4b, to terminal o.

Since this circuit is supplied with coded current of normal polarity, contacts 17 and 20 of relay CP will close alternately in their left-hand and deenergized positions, following the code of the 45 current which energizes relay CP. Secondary winding 19 of transformer AT will therefore be energized, causing relay AD to be energized. With relay AD energized, the circuits for relay HD 50 are open at contact 39 of relay AD.

55 Also, with relay AD energized, semaphore arm 82 of unit A of signal 4b will occupy the 90° position, under the control of circuits passing from terminal b, through front points of contacts 75 and 77 of relay AD, and the mechanism of signal 4b to terminal o. With relay AD energized, the circuit for lamp Y of the lower unit B of signal 4b will be open at contact 78 of relay AD.

60 Whenever a train occupies the next block in the rear of signal 4b, lamp 81 of upper unit A of signal 4b will be lighted by a circuit passing from terminal b, through contact 63 of relay ER, and lamp 81 to terminal o.

Assuming now that a train passes signal 4b, 65 causing relay 4TR to become deenergized, contact 41 of this relay will open the circuit for relay CP, causing relay CP to also be deenergized, and preventing relay HD from becoming energized. With relays AD and HD deenergized, the arm of 70 signal 4b will move to the horizontal position, and lamp Y of unit B of signal 4b will remain unlighted.

When the train clears the block of signal 4b and occupies the second block in advance of signal 75 4b, relay HD will become energized by steady

current of reverse polarity passing from terminal b, through the winding of relay ER for the next signal in advance of signal 4b, a resistor 74, contact 73 operated by the next signal in advance, now closed in the lower position, conductor 72, 5 winding of relay HD, contact 39 of relay AD, contact 41 of relay 4TR, conductor 42, contact 43 of relay a4TR, contact 71 operated by the next signal in advance of signal 4b, now occupying its lower position, to terminal o.

10 With relay HD energized by current of reverse polarity and relay AD deenergized, a circuit will be complete for causing the arm of signal 4b to move to the 45° position, this circuit passing from terminal b, through the back point of contact 75 15 of relay AD, contact 76 of relay HD, and the mechanism of signal 4b to terminal o. With relay HD energized by current of reverse polarity, contact 80 of this relay will be open, and hence lamp Y of the lower unit B of signal 4b will re- 20 main unlighted.

If, now, the train moves into the third block in advance of signal 4b, leaving the first two blocks unoccupied, relay HD for signal 4b will become energized by current of normal polarity 25 passing from terminal b, through the winding of relay ER for the next signal in advance of signal 4b, a resistor 74, contact 68 of relay HD for the next signal in advance, closed in the right-hand position, front point of contact 60 of relay HD 30 for the next signal in advance, contact 71 operated by the next signal in advance, contact 43 of relay a4TR, conductor 42, contact 41 of relay 4TR, contact 39 of relay AD, winding of relay HD, conductor 72, and contact 73 of the next 35 signal in advance, to terminal o. Since the current supplied to this circuit is uncoded, relay CP will retain its contacts 17 and 20 in the left-hand position, and hence secondary winding 19 of transformer AT will remain deenergized, leaving 40 relay AD also deenergized.

With relay AD deenergized and with relay HD energized by current of normal polarity, the arm of signal 4b will be retained in the 45° position by the circuit previously traced. Lamp Y of lower 45 unit B, when a train occupies the next block in the rear of signal 4b, will now be lighted by a circuit passing from terminal b, through contact 63 of relay ER, contact 78 of relay AD, contacts 79 and 80 of relay HD, and lamp Y to terminal o.

If the train now moves into the fourth block 50 in advance of signal 4b, leaving the first three blocks in advance unoccupied, relay CP will become energized by coded current passing from terminal b, through the winding of relay ER for the next signal in advance of signal 4b, contact 55 58 operated by coding device CT for the next signal in advance, contact 68 of the relay HD for the next signal in advance in the left-hand position, front point of contact 60 of relay HD for the next signal in advance, contact 71 operated by the next signal in advance, contact 43 of relay a4TR, conductor 42, contact 41 of relay 4TR, winding of relay CP, conductor 72, and contact 73 of the next signal in advance to terminal o. 60 With relay CP energized by coded current, relay AD will become energized, causing the arm of signal 4b to be operated to the 90° position by the circuits previously traced.

From the foregoing description and the accompanying drawings, it follows that in apparatus embodying my invention, I have provided means for controlling the signals in multiple block signaling systems to display a plurality of indications, by the use of constant and coded 75

current of normal and reverse polarities and by coded current impulses of a given polarity alternated with coded current impulses of the opposite polarity supplied to a given pair of conductors and controlled by traffic conditions in advance. By using also current coded at one or more other frequencies in apparatus embodying my invention, the signals can be controlled to display still more indications, thus increasing the number of blocks by which the signal can be controlled. Apparatus embodying my invention also protects the signaling system from inductive interference and capacity feed from adjacent power lines.

It is to be understood that apparatus embodying my invention is not limited to the particular types of signals and signal aspects here shown, nor to three block and five block systems. It can also be used for four block signaling systems and for systems providing signal indications by each signal for more than five blocks.

Although I have herein shown and described only a few forms of railway signaling embodying my invention, it is understood that various changes and modifications may be made therein within the scope of the appended claims without departing from the spirit and scope of my invention.

Having thus described my invention, what I claim is:

1. In combination, a stretch of railway track divided into blocks, a signal for each of said blocks for governing traffic movements into the associated block, a polarized code following relay for each of said signals, normal contacts of each of said relays closed in a normal position when the corresponding relay is energized by current of normal polarity and closed in a deenergized position when said relay is deenergized or is energized by current of reverse polarity, reverse contacts of each of said relays closed in a reverse position when the corresponding relay is energized by current of reverse polarity and closed in a deenergized position when the relay is deenergized or is energized by current of normal polarity, a slow release normal decoding relay and a slow release reverse decoding relay for each of said code following relays, a normal decoding transformer for each of said normal decoding relays, a reverse decoding transformer for each of said reverse decoding relays, means controlled by normal and reverse polar contacts of each of said polarized code following relays for energizing the corresponding normal and reverse decoding transformers while said contacts are being operated in response to coded current, means controlled by each of said normal and reverse decoding transformers and by normal and reverse contacts respectively of the corresponding polarized code following relay for energizing the corresponding normal and reverse decoding relays respectively, a coding device for each of said signals, a pair of conductors for each of said signals across which the associated polarized code following relay is connected, a polarized signal control relay of the retained neutral contact type for each of said signals connected across the corresponding pair of conductors through back contacts of the associated normal and reverse decoding relays in series, traffic controlled means for each of said blocks, means controlled by the coding device for each signal and by the normal and reverse decoding relays and polarized signal control relay for the same signal and by the traffic controlled means for the next block in the rear for energizing the conductors for the next signal in the rear by steady current of normal or reverse polarity or by coded current of normal or reverse polarity or by code impulses of normal polarity alternately with code impulses of reverse polarity if said next block in the rear is unoccupied, and means controlled by the normal and reverse decoding relays and the polarized signal control relay for each signal for operating the corresponding signal to display five different indications one for each of said five forms of current supplied to the conductors for directing traffic movements into the block and for operating the corresponding signal to display a stop indication if the block is occupied by a train.
2. In combination, a stretch of railway track divided into blocks, a signal for each of said blocks for governing traffic movements into the associated block, a pair of conductors for each of said signals, a polarized code following relay for each of said signals connected across the associated pair of conductors, a normal and a reverse decoding transformer for each of said code following relays, a normal and a reverse slow release decoding relay for each of said code following relays, means controlled by each of said code following relays for energizing the associated normal decoding relay through the associated normal decoding transformer when the corresponding code following relay is energized by coded current of normal polarity from its pair of conductors, means controlled by each of said code following relays for energizing the associated reverse decoding relay through the associated reverse decoding transformer when the corresponding code following relay is energized by coded current of reverse polarity from its pair of conductors, a polarized signal control relay of the retained neutral contact type for each of said signals connected across the associated pair of conductors through back contacts of the associated normal and reverse decoding relays in series, a coding device for each of said signals, means controlled by the coding device for each signal and by the normal and reverse decoding relays and polarized signal control relay for the same signal as well as by traffic conditions in the next block in the rear for energizing the conductors for the next signal in the rear by steady or coded current of normal or reverse polarity or by code impulses of current of normal polarity alternately with code impulses of current of reverse polarity if said next block in the rear is unoccupied, and means controlled by the normal and reverse decoding relays and the polarized signal control relay for each signal for operating the corresponding signal to display five different indications one for each of said five forms of current for directing traffic movements into the block and for operating the corresponding signal to display a stop indication if the block is occupied by a train.
3. In combination, a stretch of railway track divided into blocks, a signal for each of said blocks for governing traffic movements into the associated block, a pair of conductors for each of said blocks, a polarized code following relay for each of said signals controlled by current of normal and reverse polarities in said conductors, a normal and a reverse decoding relay for each of said code following relays, means controlled by each of said code following relays for energizing the associated normal and reverse decoding relays when the code following relay is energized by coded current of normal and reverse polarities respectively, a polarized signal control relay for each of said signals controlled by steady current

in the rear by steady current of normal or reverse polarity or by coded current of normal or reverse polarity or by code impulses of normal polarity alternately with code impulses of reverse polarity if said next block in the rear is unoccupied, and means controlled by the normal and reverse decoding relays and by the polarized signal control relay for each signal for operating the corresponding signal to display five different indications one for each of said five forms of current supplied to the conductors for directing traffic movements into the block and for operating the corresponding signal to display a stop indication if the block is occupied by a train.

5 10 15 20 25 30 35 40 45 50 55 60 65 70 75

of normal and reverse polarities in the associated pair of conductors through back contacts of the associated normal and reverse decoding relays in series, a coding device for each of said signals, 5 means controlled by the coding device for each of said signals and by the normal and reverse decoding relays and polarized signal control relay for the same signal as well as by traffic controlled means for the next block in the rear for 10 energizing the conductors for the next block in the rear by steady or coded current of normal or reverse polarity or by impulses of coded current of normal polarity alternately with impulses of coded current of reverse polarity if the next 15 block in the rear is unoccupied, and means controlled by the decoding relays and the polarized signal control relay for each signal for energizing the corresponding signal to display five different indications one for each of said five conditions of current for directing traffic movements 20 into its block if its block is unoccupied.

4. In combination, a stretch of railway track divided into blocks, a signal for each of said blocks 25 for governing traffic movements into the associated block, a pair of conductors for each of said blocks, a polarized code following relay for each of said signals controlled by current of normal and reverse polarities in said conductors, a normal and a reverse decoding relay for each 30 of said code following relays, means controlled by each of said code following relays for energizing the associated normal and reverse decoding relays when the code following relay is energized by coded current of normal and reverse 35 polarities respectively, a polarized signal control relay for each of said signals controlled by steady current of normal and reverse polarities in the associated pair of conductors through back contacts of the associated normal and reverse decoding 40 relays in series, means selectively controlled by traffic conditions on said stretch of railway track for energizing the conductors for each block by steady or coded current of normal or reverse polarity or by impulses of coded current of 45 normal polarity alternately with impulses of coded current of reverse polarity, and means controlled by the decoding relays and the polarized signal control relay for each signal for operating the corresponding signal to display five 50 different indications for directing traffic movements into the associated block.

5. In combination, a stretch of railway track divided into blocks, a signal for each of said blocks, code responsive means for each of said signals selectively responsive to coded current of normal and reverse polarities, a normal and a reverse decoding device, means controlled by said code responsive means for operating said normal and reverse decoding devices when coded current 55 of normal and reverse polarities respectively energize said code responsive means, a polarized relay for each signal, means controlled by given traffic conditions in advance of each signal and by the decoding devices for the same signal in 60 advance of the signal are clear while the third block is occupied or the first block in advance is clear while the second block is occupied, means controlled by other given traffic conditions in advance of each signal for energizing the code responsive means for that signal by coded current of normal or reverse polarity, and means controlled by the polarized relay and the normal and reverse decoding devices for each signal for operating the corresponding signal to 65 display four different indications one for each of said four forms of current.

6. In combination, a stretch of railway track 70 divided into blocks, a signal for each of said blocks, code responsive means for each of said signals selectively responsive to coded current of normal and reverse polarities, a polarized relay for each of said signals, means controlled by the code responsive means for each signal when energized by coded current for preventing energization of the polarized relay for the same signal, means controlled by given traffic conditions in advance of each signal for energizing the code 75

larity alternately with impulses of coded current of reverse polarity, and means controlled by the polarized relay and the normal and reverse decoding devices for each signal for operating the corresponding signal to display five different indications one for each of said five forms of current and to display a stop indication when said polarized relay and said decoding devices are deenergized.

6. In combination, a stretch of railway track 10 divided into blocks, a signal for each of said blocks, code responsive means for each of said signals selectively responsive to coded current of normal and reverse polarities, a polarized relay for each of said signals, means controlled by the code responsive means for each signal when energized by coded current for preventing energization of the polarized relay for the same signal, means controlled by given traffic conditions in advance of each signal for energizing the code 15 responsive means for the corresponding signal by coded current of normal or reverse polarity or by impulses of coded current of normal polarity alternately with impulses of coded current of reverse polarity, means controlled by other given traffic conditions in advance of each signal for energizing the polarized relay for the same signal by steady current of normal or reverse polarity, and means controlled by the polarized relay and by the code responsive means for each 20 signal for operating their signal to display a corresponding indication for each of said conditions of current for directing traffic movements into the associated block and a stop indication when said polarized relay and code responsive 25 means are deenergized.

7. In combination, a stretch of railway track divided into blocks, a signal for each of said blocks, code responsive means for each of said signals selectively responsive to coded current of 30 normal and reverse polarities, a normal and a reverse decoding device, means controlled by said code responsive means for operating said normal and reverse decoding devices when coded currents of normal and reverse polarities respectively energize said code responsive means, a polarized relay for each signal, means controlled by given traffic conditions in advance of each signal and by the decoding devices for the same signal in the deenergized condition for energizing 35 the polarized relay for that signal by current of normal or reverse polarity according as the first two blocks in advance of the signal are clear while the third block is occupied or the first block in advance is clear while the second block is occupied, means controlled by other given traffic conditions in advance of each signal for energizing the code responsive means for that signal by coded current of normal or reverse polarity, and means controlled by the polarized relay and the normal and reverse decoding devices for each signal for operating the corresponding signal to 40 display four different indications one for each of said four forms of current.

8. In combination, a stretch of railway track 45 divided into blocks, a signal for each of said blocks, code responsive means for each of said signals selectively responsive to coded current of normal and reverse polarities, a polarized relay for each of said signals, means controlled by the code responsive means for each signal when energized by coded current for preventing energization of the polarized relay for the same signal, means controlled by given traffic conditions in advance of each signal for energizing the code 50

- responsive means for the corresponding signal by coded current of normal or reverse polarity, means controlled by other given traffic conditions in advance of each signal for energizing the 5 polarized relay for the same signal by steady current of normal or reverse polarity, and means controlled by the polarized relay and by the code responsive means for each signal for operating that signal to display a corresponding indication 10 for each of said conditions of current for directing traffic movements into the associated block.
9. In combination, a stretch of railway track divided into blocks, a signal for each of said blocks, code responsive means for each of said 15 signals selectively responsive to coded current for opening a given contact only when energized by coded current of a given polarity, a control relay for each of said signals, means controlled by a given traffic condition in advance of each signal 20 for energizing the code responsive means for the corresponding signal by coded current of said given polarity, means controlled by a second given traffic condition in advance of each signal for energizing the control relay for the corresponding 25 signal only if the given contact for the code responsive means for the same signal is closed, and means controlled by the control relay and the code responsive means for each signal for controlling the corresponding signal to display a first 30 or a second indication corresponding to said first and second given traffic conditions respectively.
10. In combination, a stretch of railway track, a signal for governing traffic movements into said stretch, a signal control relay, a circuit for 35 energizing said signal control relay under a given traffic condition on said stretch of track, code responsive means selectively responsive in a given manner to current of only a given polarity, means controllable by said code responsive means for opening said circuit for said signal control relay 40 only when coded current of said given polarity energizes said code responsive means, means for energizing said code responsive means by coded current of said given polarity under a second given traffic condition, and means controlled by 45 said control relay and said code responsive means for controlling said signal to display a first or a second indication corresponding to said first and second given traffic conditions.
- 50 11. In combination, a stretch of railway track, a signal for governing traffic movements into said stretch, a signal control relay, code responsive means selectively responsive to coded current of a given polarity, a decoding relay, means controlled by said code responsive means for energizing said decoding relay only when coded current of said given polarity energizes said code responsive means, a circuit including a back contact of said decoding relay for energizing said 55 signal control relay under a given traffic condition on said stretch of track, a second circuit controlled by a second given traffic condition on said stretch of track for energizing said code responsive means by coded current of said given po-
- larity, a slow release repeater relay, a circuit including a front contact of said decoding relay for energizing said slow release repeater relay, and means controlled by said signal control relay and said slow release repeater relay for controlling said signal to display a first or a second indication when one or the other of said signal control and slow release repeater relays is energized and to display a stop indication when said signal control and slow release repeater relays 10 are both deenergized.
12. In combination, a stretch of railway track, a signal for governing traffic movements into said stretch, a polarized signal control relay, code responsive means selectively responsive to coded 15 current of a given polarity, means controlled by a first and second given traffic condition on said stretch of track for energizing said polarized signal control relay by current of normal and reverse polarities respectively, means controlled by 20 a third given traffic condition on said stretch of track for energizing said code responsive means by coded current of said given polarity, means controllable by said code responsive means only when energized by coded current of said given 25 polarity for preventing energization of said polarized signal control relay, and means controlled by said polarized signal control relay when energized by current of normal or reverse polarity and by said code responsive means when energized by coded current of said given polarity for controlling said signal to display a first or a second or a third indication respectively.
13. In combination, a stretch of railway track divided into a first and a second and a third section, a signal for governing traffic movements into said stretch, a polarized signal control relay, code responsive means selectively responsive to coded current of a given polarity, a first and a second and a third traffic responsive device controlled by traffic conditions in said first and second and third sections respectively, means controlled by said traffic responsive devices for energizing said polarized signal control relay by current of reverse or normal polarity according 35 as said first section is unoccupied while said second section is occupied or said first and second sections are unoccupied while said third section is occupied, means controlled by said traffic responsive devices for energizing said code responsive means by coded current of said given polarity when all three sections are unoccupied, means controllable by said code responsive means only when energized by coded current of said given 40 polarity for preventing energization of said polarized signal control relay, and means controlled by said polarized signal control relay when energized by current of normal or reverse polarity and by said code responsive means when energized by coded current of said given polarity for controlling said signal to display a first or a second or a third indication respectively.
